Patented Apr. 3, 1962

192,530

COMBINED COFFEE PERCOLATOR AND STAND THEREFOR

David L. Painter, Glenview, Ill., assignor to The West Bend Company, West Bend, Wis., a corporation of Wisconsin

Filed July 31, 1961, Ser. No. 66,129

Term of patent 14 years

(Cl. D44—26)

FIG. 1

Des. 192,530

PAGE 2

FIG. 2

FIG. 5

FIG. 3

FIG. 4

FIG. 1 is a view in front elevation of a combined coffee percolator and stand therefor showing my new design;

FIG. 2 is a side elevational view;

FIG. 3 is a top plan view;

FIG. 4 is a bottom plan view; and

FIG. 5 is a sectional view through the cover, taken on line 5—5 of FIG. 3.

I claim:

The ornamental design for a combined coffee percolator and stand therefor as shown.
